UNITED STATES PATENT OFFICE.

CHARLES L. ENGEL AND WALTER S. ENGEL, OF KANSAS CITY, MISSOURI.

LOOSE-LEAF BOOK.

Application filed February 4, 1924. Serial No. 690,447.

To all whom it may concern:

Be it known that we, CHARLES L. ENGEL and WALTER S. ENGEL, citizens of the United States, residing at Kansas City, in the county of Jackson and State of Missouri, have invented a certain new and useful Improvement in Loose-Leaf Books, of which the following is a specification.

Our invention relates to improvements in loose leaf books.

It is particularly well adapted for use in connection with heavy books of record in which the back and covers are connected by metal hinges, and in which the leaves are mounted on leaf supporting posts arranged to be freed at either end for the insertion or removal of leaves.

One of the objects of our invention is to provide novel means for releasably supporting both ends of the leaf supporting posts, in a manner such that the covers may be freely swung on the metal hinges.

A further object of our invention is to provide novel means for temporarily locking the post holding members in the post engaging position, to prevent unauthorized removal of leaves from the posts.

A further object of our invention is to provide novel means for non-releasably locking the post holding members in the post engaging position, when it is no longer desired to remove, insert or change the leaves.

The novel features of our invention are hereinafter fully described and claimed.

In the accompanying drawing which illustrates the preferred embodiment of our invention,

Fig. 1 is a plan view, partly broken away, of our improved loose leaf book.

Fig. 2 is an enlarged section on the plane of the line 2—2 of Fig. 1, showing one of the leaf supporting posts and leaves mounted thereon.

Fig. 3 is an enlarged longitudinal sectional view of one of the housings and the post-holding member mounted therein, the latter and the housing being partly broken away.

Fig. 4 is a view similar to Fig. 3, of an end portion of the housing and a portion of the post-holding member shown in the released position.

Fig. 5 is an enlarged cross section on the plane of the line 5—5 of Fig. 1, the leaves being omitted.

Fig. 6 is a perspective view of a portion

of one of the housings and the post holding member mounted therein.

Fig. 7 is a perspective view of a portion of the inner back member.

Fig. 8 is a perspective view of one of the hinge pintles.

Fig. 9 is a perspective view of a portion of one of the metal hinge members.

Fig. 10, is a plan view of a key to be used in releasing the pivoted locking members from the post holding members, when it is desired to withdraw the latter to the released position.

Fig. 11, is an enlarged section on the line 11—11 of Fig. 1.

Fig. 12, is an enlarged section on the line 12—12 of Fig. 1.

Similar reference characters designate similar parts in the different views.

The back of the book comprises an inner channel sheet metal member 1, provided at its longitudinal edges with pintle barrels 2, in which are respectively mounted two hinge pintles 3.

4 designates an outer channel back member which is secured to the outer side of the back member 1, by screws 5, having heads at their inner ends and fitted in threaded holes in the outer back member 4. To prevent accidental loosening of the screws, the heads thereof may be soldered to the back member 1.

6 designates two metal hinge plates, each having at its inner edge barrels 7 through 90 which the adjacent pinte 3 extends.

The back member 4 at its ends is provided respectively with two arcuate inwardly extending flanges 8, arranged to cover the adjacent ends of the pintles 3, to prevent the accidental removal of the latter.

9 designates two outer cover members, each of which may be composed of heavy cardboard or other material, and upon the inner side of which is fastened the adjacent hinge member 6.

Respectively mounted upon the inner sides of the cover members 9, are two inner cover members, which may be heavy cardboard, and which may respectively overlap the hinge plates 6. Each of the latter has transverse openings 11, through which the adjacent cover member is pressed, such pressed portion being glued to the inner side of the adjacent outer cover member 9 (see the right cover in Fig. 2) thereby securely attaching the cover member 9 and 10 to the hinge

plates 6, without the use of rivets or other accessory fastening means.

12 designates two longitudinal tubular members constituting housings in which are 5 respectively slidably mounted two post holding members 13, each of which is provided with longitudinal prongs 14, which are adapted to be extended through the adjacent end portions of arcuate leaf supporting posts 15, which extend parallel with each other transversely across the back member 1. Each housing 12, is provided with openings 16, adapted to receive therein, respectively, the adjacent ends of the 10 posts 15.

Each housing 12, is provided with longitudinal barrels 17, through which extends the adjacent pintle 3. By means of this construction, the housings 12 may be swung on 20 the pintles 3 independently of the covers.

Each post holding member 13, is longitudinally slidable to and from a position in which the prongs 14, will extend across the openings 16 and through the posts 15.

25 In Fig. 3, the post holding member 13, is shown in solid lines in the holding position. In Fig. 4, the member 13 is shown withdrawn from the holding position, to permit the adjacent housing 12 being swung to release the adjacent ends of the posts 15, to 30 permit the removal from or insertion on the posts of loose leaves 18.

Each member 13, outside of the adjacent housing, has at one side a transverse groove 35 19, from which extends laterally an arm 20, which serves as a finger hold for sliding the member 13 to and from the holding position.

To releasably lock post holding member 40 13, in the holding position, there is pivotally mounted on a transverse pin 21, a locking member 22, in the adjacent housing member 12. The inner end of each locking member 22, has a lateral arm 23, adapted 45 to engage a shoulder 24, provided on the member 13, in a position such as to be engaged by the arm 23, when the prongs 14 are in the holding position, as shown in solid lines in Fig. 3.

50 For releasing the locking member 22, from engagement with the shoulder 24, there is provided, Fig. 10, a key 25 having at one end a T-shaped head 26, which is adapted to be inserted through a key hole 55 27, Fig. 6, of the adjacent housing 12. After the key has been inserted and turned, and the holding member 13 has been withdrawn until the member 22 is clear of the shoulder 28, the key will engage the locking member 22 at the inner side of the pivot pin 21, thereby forcing the locking member 22, to the released position, shown in Fig. 4, the holding member 13, may then be withdrawn by means of the arm 20, to 60 the released position, shown in Fig. 4, in

which position, the inner end of the locking member 22, will contact with a shoulder 27, provided on the holding member 13, thereby limiting the outward movement of the holding member 13.

Leaves may now be placed on or removed from the posts 15, the adjacent housing 12 having been swung outwardly so as to release the posts. After the posts 15 have been reinserted in the housing 12, the withdrawn holding member 13, is forced inwardly, the key 25 having been withdrawn, until a rounded shoulder 28, with which the member 13 is provided engages the adjacent rounded edge of the locking member 22, as shown in solid lines in Fig. 3. Continued inward movement of the member 13 will force the locking member 22, to the locking position, in which position the arm 23 of the locking member will be in the path of movement of the shoulder 24, thus preventing any one from withdrawing the prongs 14, from the posts 15, unless such person is provided with a suitable key for releasing the locking member 22, as 90 above described.

When it is desired to permanently lock the post holding members 13, in their holding position, so that no one can release the holding members so as to remove or insert leaves, the arm 20 of each holding member 13, is broken off or bent at the groove 19 into alignment with the body of the member 13, so that the latter can be forced inwardly to the permanently locked position, shown in 100 dotted lines in Fig. 3.

In each housing 12, at the end opposite to the end adjacent to the arm 20, is rigidly fastened a locking member 29, which completely fills and closes that end of the housing 12. The inner end of the locking member 29, is provided with a beveled edge 30, which terminates at a shoulder 31, on the locking member 29, which is adapted to be lockingly engaged by a shoulder 32, provided on a resilient arm 33, with which the adjacent end of the holding member 13, is provided. When the holding member 13 is forced inwardly, from the position shown in solid lines in Fig. 3, the adjacent beveled edge of the arm 33, will have sliding contact with the beveled edge 30, until the shoulder 32 passes and springs into locked engagement with the shoulder 31, as shown in dotted lines in Fig. 3. The locking member 13 is then permanently locked in the post holding position and can not be removed from such position.

Each outer cover member 9, has mounted on each end edge and longitudinal outer edge, a channel binding member 34, which embraces the outer side of member 9, and a raised portion 35, at the inner side of said member. The inner edge of each binding member 34, has a longitudinal portion 36,

- which embraces the inner edge of the adjacent raised portion 35, and which is provided with an inwardly extending flange 37, upon which rests the inner cover member 10. 5 The latter thus serves the double function of fastening the hinge plates 6, and the binding members 34 to the outer cover member 9, without the use of rivets and similar accessory fastening devices.
- 10 When it is desired to remove sheets from or place them on the posts 15, at either set of ends of the latter, the key 25 is used in the manner as described, to release the desired post holding member 13, from the adjacent locking member 22. After such release, the member 13 is withdrawn to the position shown in Fig. 4, after which, the adjacent housing 12 may be swung outwardly, to clear the posts 15, so that the leaves 20 may be placed on the latter or removed therefrom. The housing 12 is then restored to engagement with the posts 15, following which, after removal of the key, the withdrawn post holding member 13, is again forced to the holding position, shown in solid lines in Fig. 3, in which it will be held by the temporary locking member 22.
- We do not limit our invention to the structure shown and described, as many modifications, within the scope of the appended claims may be made without departing from the spirit of our invention.
- What we claim is.
- 35 1. In a loose leaf book, a housing, a post holding member longitudinally movable in said housing to and from a position in which it is adapted to engage and hold a leaf supporting post, and a temporary locking member pivoted to and in the housing and arranged to be engaged by said post holding member for releasably holding the latter in the holding position and movable by said post holding member to the locking position with the latter, and adapted to be released by a key.
- 40 2. In a loose leaf book, a housing, having a key hole, a post holding member longitudinally movable in said housing to and
- from a position in which it is adapted to be engaged by and hold a leaf supporting post 50 and having two shoulders, and a temporary locking member pivoted to and in said housing and adapted to be engaged by one of said shoulders and thereby forced into position for locking engagement with the other 55 of said shoulders for locking the post holding member from being moved from the locking position and adapted to be released from such locked engagement by a key inserted into said key hole.
- 60 3. In a loose leaf book, a housing having a solid rigid locking member mounted in and closing one end of said housing, a post holding member longitudinally movable in said housing to and from a position in which it is adapted to engage and hold a leaf supporting post and having a resilient arm adapted when moved to a permanent locking position to lock with said locking member, and provided with releasable means for holding it from moving to such permanent locking position, and key released means for temporarily locking the post holding member in the post holding position.
- 65 4. In a loose leaf book, a housing having 70 in one end a rigid immovable locking member closing said end, and having in one side a keyhole, a post holding member longitudinally movable in said housing to and from a position in which it is adapted to 75 engage and hold a leaf supporting post, and provided with a resilient arm adapted to lock with said locking member to hold the post holding member permanently locked, the post holding member having releasable 80 means for being held by the housing from moving to the permanent locking position, and a temporary locking member pivoted in said housing and thereto and arranged to engage and hold the post holding member 85 in the post engaging position and releasable by a key inserted through said key hole.
- 90 In testimony whereof we have signed our names to this specification.

CHARLES L. ENGEL.
WALTER S. ENGEL.
